OPTICAL READERS FOR AUTOMATIC DATA PROCESSING

Wayne L. Aderman, Rochester, Minn., assignor to Inter-
national Business Machines Corporation, Armonk, N.Y.

Filed Mar. 22, 1973, Ser. No. 344,000

Term of patent 14 years

Int. Cl. D14—02

U.S. Cl. D26—5 C

FIG. 1

FIG. 2

FIG. 3

FIG. 4

FIG. 1 is a front perspective view of a first embodiment of an optical reader for automatic data processing, showing my new design;

FIG. 2 is a rear perspective view of the embodiment shown in FIG. 1;

FIG. 3 is a front perspective view of a second embodiment of an optical reader for automatic data processing showing my new design;

FIG. 4 is a rear perspective view of the embodiment shown in FIG. 3.

I claim:

The ornamental design for optical readers for automatic data processing, as shown.
